UNITED STATES PATENT OFFICE.

JOSEF NICHT, OF AUBURN, NEW YORK, ASSIGNOR OF ONE-HALF TO
ALEXANDER J. NICHT, OF SAME PLACE.

FLOUR-BOLT.

SPECIFICATION forming part of Letters Patent No. 288,845, dated November 20, 1883.

Application filed September 19, 1882. (No model.)

To all whom it may concern:

Be it known that I, JOSEF NICHT, of Auburn, in the county of Cayuga and State of New York, have invented new and useful Improvements in Flour-Bolts, of which the following is a specification.

This invention relates more particularly to that class of flour-bolts which consist of a rotating cylinder covered with bolting-cloth and a series of beaters revolving within the cylinder, whereby the flour is driven through the meshes of the bolting-cloth.

The object of my invention is to improve the construction and operation of such flour-bolts; and my invention consists of the particular improvements hereinafter described, and pointed out in the claims.

In the accompanying drawings, consisting of two sheets, Figure 1 is a longitudinal sectional elevation of a flour-bolt provided with my improvements. Fig. 2 is an elevation of the front end of the bolt with the casing removed. Fig. 3 is a cross-section thereof. Fig. 4 is a longitudinal sectional elevation, on an enlarged scale, of the feed end of the flour-bolt. Fig. 5 is a similar view, showing a modified construction of the mechanism. Fig. 6 is a cross-section in line $x-x$, Fig. 4. Fig. 7 is a cross-section in line $y-y$, Fig. 5.

Like letters of reference refer to like parts in the several figures.

A represents the stationary frame of the machine, and A' the inclosing case secured thereto.

B represents the bolting-cylinder, arranged in the casing A' and covered with bolting-cloth b , which may be applied in sections having different degrees of fineness, according to the work which the bolt is designed to perform.

C represents the annular head at the feed end of the bolt, and C' the annular head at the tail end of the bolt. Both heads are supported on and revolve on grooved rollers c, c' , respectively. c^2 represents longitudinal stays, which connect the annular heads C, C' .

C^2 represents an intermediate annular head, arranged between the heads C, C' at the tail end of the bolting-cloth b , the cylinder being

covered between the heads C and C^2 with perforated metal or wire-gauze c^3 . The stays c^2 are provided with sleeves or other shoulders between the several heads, whereby the latter are kept in their proper relative position. The bolting-cloth b is secured to the heads C and C^2 by means of pins or sharp points d , which project from the outer surface of that portion of each head to which the ticking is secured which is sewed to the edge of the bolting-cloth. This ticking is stretched and pressed down over these pins, which penetrate the ticking and hold it in place. The ticking is further secured by an expansible clamping-ring, d' , which is applied to the outer side of the ticking, as shown in Figs. 3 and 4. The pins d are preferably secured to a ring, d^2 , of leather, which is secured to the respective heads C, C^2 by screws or other suitable means. The bolting-cloth b is provided with rings d^3 , as described in former Letters Patent, No. 250,952, granted to me December 18, 1881, and these rings are struck from time to time by a knocker, d^4 , to detach the material adhering to the bolting-cloth.

e represents rotary beaters arranged in the bolting-cylinder B , and secured to a shaft, e' , which is supported in bearings e^2 , and provided at its front end with a pulley, e^3 , by which the shaft is rotated. f represents the feed-spout, whereby the material to be bolted is introduced into the machine. f' is a cylinder or tube, which surrounds the shaft e' , and which receives the material from the feed-spout f . This tube is firmly secured to the stationary casing of the machine by bolts f^2 or otherwise.

g is a screw-conveyer secured to the shaft e' , within the tube f' , in such manner as to propel the material toward the rear end of the bolting-cylinder.

g' is a rearward extension of the tube f' . This extension is secured to the shaft e' so as to rotate therewith, and is enlarged in diameter toward its rear end, to facilitate the passage of the material to the discharge-openings g^2 , formed in the rear end of the extension g' . The front end of the extension is secured to a ring, h , which is supported by arms h' , cast on

the hub of the screw-conveyer g . The front side of the ring h fits snugly against the rear edge of the tube f' , to prevent the material from escaping between the rotating and stationary portions of the tube. The rear end of the tubular extension g' is supported by a spider, h^2 , secured to the shaft e' .

I represents a short bolting-jacket inclosing the feed mechanism, and receiving the material to be bolted before it enters the cylinder B , for the purpose of effecting a preliminary separation of all coarse particles contained in the meal from the finer particles, which alone are delivered into the bolting-cylinder.

15 The bolting-jacket I is constructed of wire-cloth or perforated metal of the proper mesh to permit the fine meal to pass through its openings, while the coarse particles—such as dough-balls, nails, &c.—are prevented from 20 entering the cylinder B , and discharged through an opening, i , in the front wall of the jacket. The jacket I is preferably made tapering rearwardly, to facilitate the discharge of the coarse material from the jacket. Its front end is secured to a disk, i' , attached to the front wall 25 of the casing A' , and its rear end is closed and supported by a disk, i^2 , which is provided with a central opening, through which the shaft e' passes loosely. The disk i^2 is secured to the 30 disk i' by stays i^3 .

j are rotating brushes arranged within the jacket I , so as to brush the inner surface thereof, and secured with their front ends to arms j' , and with their rear ends to the spider h^2 .

35 k are rotating brushes arranged outside of the jacket I , to brush the outer surface thereof. Their front ends are secured to the head C of the bolting-cylinder B and their rear ends to a spider, K , secured to the shaft e' in rear of the disk 40 i^2 of the jacket I . The material fed into the machine through the feed-spout f enters the tube f' , and is moved inwardly by the conveyer g , and finally discharged from the tube g' into the jacket I at its inner end. The fine material 45 is brushed through the meshes of the jacket I , while the coarse material is discharged through the opening i . The fine meal entering the bolting-cylinder B from the jacket I is now bolted through the bolting-cloth b , and separated according to its different degrees of 50 fineness. The flour is bolted through the bolting-cloth b , and the coarse valuable particles—such as middlings—through the perforated metal, c^3 . The casing A' is provided with 55 transverse partitions l l' at the heads C C^2 , respectively, whereby the flour-space L is separated from the space L' , into which the coarser material is discharged.

m is a screw-conveyer arranged in the bottom 60 of the hopper or trough, which receives the bolted material, and which may be provided with a suitable number of openings, m' , controlled by slides, through which different portions of the bolted material may be drawn 65 off at desire. The conveyer m is actuated by an endless belt, m^2 , running around suitable

pulleys. The bolting-cylinder B is rotated from the shaft of the conveyer m by an endless belt, m^3 , running around a pulley, m^4 , on the conveyer-shaft, and a pulley, m^5 , formed on or secured to the head C of the bolting-cylinder.

N represents a tapering hood, secured to the inner side of the rear wall of the casing A' , and provided at its apex with an opening, n , surrounding the shaft e' .

n' represents an opening formed in the rear wall of the casing A' at the lowest point of the cavity of the hood N . This opening communicates with the upper end of the spout O , which receives the tailings from the cylinder 80 B through an opening, o' .

o^2 represents an opening formed in the outer wall of the spout O , opposite the opening n' , and provided with a slide, whereby the area of the opening can be regulated.

85 o^3 represents an opening or passage leading from the space L' into the spout O , and provided with a slide for adjusting its size. The beaters revolving within the cylinder B operate like fan-blades, and draw an air-current 90 upwardly through the spout O into and through the hood N and into the cylinder B . This air-current meets the tailings which descend through the spout O , and lifts the lighter particles of flour mixed with the tailings, while 95 the heavier particles of bran escape through the spout O . The force and volume of the descending air-current in the spout O can be regulated by adjusting the slides with which the openings o^2 and o^3 are provided. An upward current passes also through the discharge-spout o^4 of the space L' , and through the opening o^5 into the spout O , whereby the light particles floating in the space L' are carried over into the spout O .

100 The preliminary separating mechanism may be constructed as represented in Figs. 5 and 7, in which the bolting-jacket I is secured at its front end to the head C of the cylinder B , so as to rotate therewith, and at the rear end to a disk mounted loosely on the shaft e' . As 105 shown in Fig. 5, the screw-conveyer extends in this case to the rear end of the tube in which it is arranged, and the brushes j are stationary and rigidly secured with their front ends to the frame A of the machine, and with their rear ends to a stationary plate, p , secured to the rear end of the stationary conveyer-tube. The brushes may be arranged spirally, or at a greater or less angle with the axis of the bolt, 110 so as to move the material toward the discharge-opening i .

115 I claim as my invention—

1. The combination, with a flour-bolt, B , of a preliminary separating-bolt, I , arranged 120 within the bolt B , a feed mechanism whereby the material is delivered into the bolt I near its inner end, brushes j , whereby the fine material is brushed through the meshes of the bolt I and delivered upon the cloth of the bolt 125 B , brushes k , operating against the outer surface of the bolt I , within the bolt B , and a dis-

charge-opening, *i*, formed at the front end of the bolt *I* for the discharge of the coarse material from the bolt *I*, substantially as set forth.

2. The combination, with a flour-bolt, *B*, of

5 a preliminary bolt, *I*, arranged within the bolt *B*, brushes *j*, operating against the inner side of the bolt *I*, and brushes *k*, operating against the outer side of the bolt *I*, and revolving around the same within the bolt *B*, substantially as set forth.

10 3. The combination, with the bolt *I* and shaft *e'*, of the screw-conveyer *g*, stationary tube *f'*, and rotating tube *g'*, secured to the shaft *e'*, substantially as set forth.

15 4. The combination, with the bolt *I* and shaft *e'*, of the screw-conveyer *g*, stationary tube *f*, rotating tube *g'*, and brushes *j*, secured to the shaft *e'*, substantially as set forth.

20 5. The combination, with a bolting-cylinder, *B*, and rotating beaters *e*, of the hood *N*, arranged at the tail end of the cylinder, and the discharge-spout *O*, communicating with the

interior of the hood by an opening, *n'*, and provided with an opening, *o'*, through which the tailings enter said spout, substantially as set forth.

25 6. The combination, with a bolting-cylinder, *B*, and rotating beaters *e*, of the hood *N*, arranged at the tail end of the cylinder, and discharge-spout *O*, communicating with the interior of the hood by an opening, *n'*, and provided with an opening, *o'*, through which the tailings enter said spout, and an opening, *o²*, controlled by a slide, for admitting the external air, substantially as set forth.

30 7. The combination, with the bolting-cylinder *B*, casing *A'*, and the partition *l'*, of the hood *N* and spout *O*, provided with openings *n'* *o'* *o²* *o³*, substantially as set forth.

35 JOSEF NICHT.
